UNITED STATES PATENT OFFICE.

HARRY S. HART, OF CHICAGO, ILLINOIS.

DUMP-CAR.

1,300,962.

Specification of Letters Patent. Patented Apr. 15, 1919.

Application filed November 4, 1918. Serial No. 260,927.

To all whom it may concern:

Be it known that I, HARRY S. HART, a citizen of the United States, residing at Chicago, in the county of Cook and State 5 of Illinois, have invented certain new and useful Improvements in Dump-Cars, of which the following is a specification.

My invention relates to freight cars of the type commonly known as hopper cars, which 10 are used very largely for the transportation of coal or the like dumpable material, and has among its objects the improvement of this type of car in the manner to greatly increase the load carrying capacity of the car 15 without changing its overall dimensions and to provide such a car from which the load may be quickly discharged with a minimum amount of labor, the car being practically self cleaning.

With these and other objects which hereinafter will be pointed out, the invention 20 consists of the combination and details described in the following specification and claims.

The invention is illustrated on the accompanying sheets of drawings in which—

Figure 1 is a fragmentary side elevation of a dump car embodying my invention;

Fig. 2 is a transverse sectional view of the 30 same car taken over the trucks, and

Fig. 3 is a transverse sectional view of the same car taken intermediate the trucks.

It has been customary to build hopper cars for the transportation of coal, and like 35 commodities, having inclined end portions over the trucks discharging the load through the center of the car by means of cross hoppers or longitudinal hoppers provided with suitable dump doors. These prior constructions are well known and require no particular description for an understanding thereof. Owing to the location of the inclined end portions over the trucks, those portions 40 of the cars at the ends are largely useless for load carrying, so that any attempt to increase the capacity of these cars necessarily has been by a lengthening of the car or by increasing its height, while the discharge of the load through the car hoppers 45 is difficult, even where special unloading stations are provided owing to the necessarily restricted door openings provided in the cross hoppers. While longitudinal hoppers also have been provided in cars of this

type for discharging the load at the sides in 55 a manner to make unloading easier, attempts to apply this principle to the car have resulted in a greatly decreased load carrying capacity.

By my present invention I overcome the 60 difficulties heretofore experienced in this type of car, making it possible to carry in the car of the same length a greatly increased load, and at the same time making it possible to discharge the load at a greatly 65 reduced expenditure of time and labor.

The body of the dump car, which is carried on trucks including wheels 11 at each end of the car, comprises sides 12, ends 13, and a floor 14. The floor over the trucks 70 consists of downwardly and outwardly sloping stationary portions 15 preferably extending from a point adjacent and over the center sill 16 toward the sides of the car. The floor intermediate the trucks includes 75 stationary portions 17 which extend downwardly and inwardly from the lower edges of the car sides 12 toward the center of the car, said stationary portions 17 extending to a point and generally being located below 80 the stationary floor portions 15 over the trucks, the lower edges of the stationary floor portions 17 terminating in a plane considerably below the center sill 16.

Coöperating with the stationary A-shaped 85 floor portions over the trucks and particularly with the outer edges of the members 15 are side dump doors 18 which preferably are pivotally supported at 19 along the lower edges of the sides 12 of the car. As 90 shown in Fig. 2, these side dump doors 18 are angular in shape but it will be appreciated that flat doors may be used if desired. The side dump doors may be provided with any suitable operating mechanism, the operating mechanism here shown including operating shafts 20 around each of which is wound a chain 21 which operatively connects the shaft with the associated stationary floor portions 15, the outer edges 100 of the floor portions 15 and the swinging edges of the doors when closed forming a tight seal to prevent leakage of the material being carried by the car.

Coöperating with the downwardly and inwardly sloping floor portions 17 intermediate the trucks are flat dump doors 22 which are located in a plane considerably below

the center sill 16 and which when in closed position, as shown in full lines in Fig. 3, connect the lower edges of the floor members 17 and the lower edges of the side hopper members 23 which extend vertically downwardly from the center sill 16. These doors are located at as low a level as is practicable in order to increase the capacity of the car. Owing to this low position of these doors, it is not advisable to hinge them at their edges because of clearance conditions. It is preferable, therefore, that the doors should be opened by sliding them bodily from beneath the load. One way in which this may be done I illustrate. In the present exemplification of my invention I show the doors as pivoted at a point above the horizontal door portions so as to swing bodily, that is, these flat dump doors 22 preferably are suspended pendulum-like from frame members at pivotal centers 24, there being at the ends of the doors end plate members 25 forming hangers. It will be understood of course that as shown, these hangers may be mounted outside the end walls 25' of the longitudinal hoppers 26 intermediate the trucks and on opposite sides of the longitudinal center of the car. When in closed position, as shown in Fig. 3 of the drawings, the flat doors 22 form tight seals with the lower edges of the floor portions 17 and the vertical members 23 and may be held in such position by any suitable door operating mechanism. One example of such a mechanism is here shown which includes a center operating shaft 27 and operating chains 28 which operatively connect the shaft 27 with the doors 22. It will be noted that the centers 24 from which the doors 22 are hung are located off-center with respect to the longitudinal center line of the doors 22 so that when the operating shaft 27 is operated in a manner to slacken the chains 28 or unwrap them from the shaft 27, the doors 22 will swing outwardly as a result of their own weight and this outwardly swinging movement will be made more positive as a result of the weight of the load to be dumped. One of these dump doors 22 is shown in opened or dumping position in dotted lines in Fig. 3. To close the dump doors, it is merely necessary to actuate the operating shaft in a manner to wrap the chains 28 thereon, whereupon the dump doors 22 will move into a closed position. By means of placing the flat dump doors 22 in a horizontal plane when in closed position and at a level as far below the center sill as is permissible, the capacity of the dump car is greatly increased, it being appreciated also that by means of the floor construction over the trucks, the capacity of the car is also increased. At the same time, by means of the sloping floor portions and the dump door arrangement, the car is made self cleaning.

It is my intention to cover all modifications falling within the spirit and scope of the following claims.

I claim:

1. A car of the class described, having 70 sides, ends and a floor, the floor over the trucks comprising portions extending downwardly and outwardly toward the sides of the car, the floor between the trucks being horizontally flat and below the center sill. 75
2. A car of the class described, comprising sides, ends and a floor, the floor over the trucks comprising portions extending downwardly and outwardly toward the sides of the car, the floor between the trucks including portions extending downwardly and inwardly from the sides of the car and doors located below the center sill and normally in a horizontal plane. 80
3. A car of the class described, comprising 85 sides, ends and a floor, the floor over the trucks comprising portions extending downwardly and outwardly toward the sides of the car, the floor between the trucks including portions extending downwardly and inwardly from the sides of the car, and doors located below the center sill and normally in a horizontal plane, and side dump doors connecting the sides of the cars with the outer edges of the floor portions over the 90 trucks. 95
4. A car of the class described, comprising sides, ends and a floor, hoppers being formed intermediate the trucks on opposite sides of the center sill, the outer side walls of the 100 hopper including downwardly and inwardly extending portions, the inner walls of the hopper including vertically extending members extending downwardly from the center sill, the floor of the hoppers including substantially horizontal doors extending longitudinally of the car and mounted for pendulum-like motion located below the center sill. 105
5. A car of the class described, comprising 110 sides, ends and a floor, the floor over the trucks comprising portions extending downwardly and outwardly toward the sides of the car, the floor between the trucks including portions extending downwardly and inwardly from the sides of the car, dump 115 doors located below the center sill and normally in a horizontal plane, side dump doors connecting the sides of the cars with the outer edges of the floor portions over the trucks, and operating mechanism for said 120 doors. 125
6. A car of the class described, having sides, ends and a floor, the floor over the trucks including members extending downwardly and outwardly toward the sides of the car, the floor between the trucks being at a lower level than the floor over the trucks and including a door slidable from beneath the load. 130
7. A car of the class described having a

floor comprising downwardly and outwardly sloping portions over the trucks, the floor between the trucks being at a lower level than the portion over the trucks, said floor between the trucks comprising a substantially horizontal portion adapted to be operated to discharge the load.

8. A car of the class described having a floor comprising downwardly and outwardly sloping portions over the trucks, the floor between the trucks being at a lower level than the portion over the trucks, said floor between the trucks comprising downwardly and inwardly sloping portions and also substantially horizontal doors.

9. A car of the class described having a floor comprising downwardly and outwardly sloping portions over the trucks, the floor between the trucks being at a lower level than the portion over the trucks, said floor between the trucks comprising downwardly and inwardly sloping portions and also substantially horizontal doors, said doors being mounted for bodily swinging movement.

10. A car of the class described having a

floor comprising stationary downwardly and outwardly sloping portions over the trucks, stationary downwardly and inwardly sloping portions between the trucks at a lower level than the portions over the trucks, and a sloping portion connecting the floor portion over the trucks with the floor portion between the trucks, the floor between the trucks comprising also substantially horizontal doors.

11. A car of the class described having a floor comprising stationary downwardly and outwardly sloping portions over the trucks, stationary downwardly and inwardly sloping portions between the trucks at a lower level than the portions over the trucks, and a sloping portion connecting the floor portion over the trucks with the floor portion between the trucks, the floor between the trucks comprising also substantially horizontal doors, said doors being mounted for bodily swinging movement.

Signed at Chicago, Illinois, this 30th day of October, 1918.

HARRY S. HART.
